(57) **CLAIM**

The ornamental design for a lap desk with knee, as shown and described.

DESCRIPTION

FIG. 1 is a front side elevational view of the lap desk with knee shown in FIG. 8.

FIG. 2 is a rear side elevational view of the lap desk with knee shown in FIG. 8.

FIG. 3 is a left side elevational view of the lap desk with knee shown in FIG. 8;

FIG. 4 is a right side elevational view of the lap desk with knee shown in FIG. 8;

FIG. 5 is a top plan view of the lap desk with knee shown in FIG. 8;

FIG. 6 is a section view taken as indicated in FIG. 5 of the trough element shown in FIG. 5 of the lap desk with knee shown in FIG. 8.

FIG. 7 is a bottom plan view of the lap desk with knee shown in FIG. 8; and,

FIG. 8 is a quartering perspective view of the present invention and showing the new design.
